(57) **CLAIM**

The ornamental design for a three thickness layer wave-type tail for a soft lure, as shown and described.

DESCRIPTION

FIG. 1 is a top front perspective view of a three thickness layer wave-type tail for a soft lure showing our new design, with the tail in an exemplary wave form configuration; FIG. 2 is a bottom rear perspective view thereof; FIG. 3 is a left side elevational view thereof; FIG. 4 is a right side elevational view thereof; FIG. 5 is a top plan view thereof; FIG. 6 is a bottom plan view thereof; FIG. 7 is a front elevational view thereof; and, FIG. 8 is a rear elevational view thereof.

The broken line showing of portions of the three thickness layer wave-type tail for a soft lure is included for the purpose of illustrating only and forms no part of the claimed design.
